DESIGN FOR A RADIO TUBE SHIELD

Edward F. Staver, New York, and Frederick Hafecost, Brooklyn, N. Y., assignors to Goat Radio Tube Parts, Inc., a corporation of New York

Application February 14, 1935, Serial No. 55,428

Term of patent 14 years

To all whom it may concern:

Be it known that we, Edward F. Staver, a citizen of the United States, residing in the Borough of Queens, of the city of New York, in the State of New York, and Frederick Hafecost, a citizen of the United States, residing in the Borough of Brooklyn, of the city of New York, in the State of New York, have invented a certain new, original, and ornamental Design for a Radio Tube Shield, of which the following is a specification, reference being had to the accompanying drawing forming a part hereof.

The figure is a perspective view of a radio tube shield, embodying the design of the present invention.

The shield is circular when viewed in plan or at any horizontal section therethrough, except for slightly outwardly projecting longitudinal or upright flanges indicated at the sides of the drawing.

We claim:

The ornamental design for a radio tube shield, substantially as shown and described.

In testimony whereof, we have hereunto subscribed our names this 13th day of February, 1935.

EDWARD F. STAVER.
FREDERICK HAFECOST.
